(57) **CLAIM**

The ornamental design for an IC memory card, as shown and described.

DESCRIPTION

FIG. 1 is a perspective view of the first embodiment of an IC memory card showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a cross sectional view along the line 8—8 in FIG. 2;

FIG. 9 is a cross sectional view along the line 9—9 in FIG. 2;

FIG. 10 is a perspective view of a second embodiment of the IC memory card;

FIG. 11 is a front elevational view of FIG. 10;

FIG. 12 is a rear elevational view of FIG. 10;

FIG. 13 is a left side elevational view of FIG. 10;

FIG. 14 is a right side elevational view FIG. 10;

FIG. 15 is a top plan view of FIG. 10;

FIG. 16 is a bottom plan view of FIG. 10;

FIG. 17 is a cross sectional view taken along the line 17—17 in FIG. 11; and,

FIG. 18 is a cross sectional view taken along the line 18—18 in FIG. 11.

The interior details are omitted for clarity of illustration in FIGS. 8, 9, 17 and 18.
